HOUSE

Speros P. Andelenis, Concord, N. H.

Application September 19, 1952, Serial No. 21,519

Term of patent 14 years

(Cl. D13—1)

To all whom it may concern:

Be it known that I, Speros P. Andelenis, a citizen of the United States of America, residing at Concord, county of Merrimack, and State of New Hampshire, have invented a new, original, and ornamental Design for a House, of which the following is a specification, reference being had to the accompanying drawing, forming a part thereof, wherein:

I claim:

An ornamental design for a house, as shown.

SPEROS P. ANDELENIS.
